ELECTRIC SIGN

Andrew Varkonda, Brooklyn, N. Y.

Application August 23, 1937, Serial No. 160,522

3 Claims. (Cl. 40—130)

This invention relates to devices for displaying characters in opposite directions and more particularly to luminous signs of the rotary type.

One object of this invention is to provide a luminous sign of the rotary type. Another object of this invention is to provide an improved device for displaying characters in opposite directions. A further object of this invention is to provide means for displaying characters in such a manner as to be visible practically simultaneously and continuously at all points of the horizon. Another object is to provide a device for displaying the same characters simultaneously from opposite view-points. Other objects and advantages of this invention will appear from the following description when taken in connection with the accompanying drawings.

In the drawings Fig. 1 is a front view of a device embodying features of this invention. Fig. 2 is an end view. Fig. 3 is a plan view. Fig. 4 is a partial section on the line 4—4 in Fig. 1. Fig. 5 is a partial section on the line 5—5 in Fig. 1. Fig. 6 is a plan view on the line 6—6 in Fig. 1. Fig. 7 is a transverse cross section on the line 7—7 of Fig. 6. Fig. 8 is a front elevation of a large sign incorporating features of this invention.

Considering the drawings in greater detail, the invention contemplates a device for displaying characters in opposite directions comprising one or more characters secured on a rotatable shaft, each character being in two parts with each part secured on the opposite side of the shaft and arranged to represent each character from at least two opposing view-points, and luminous means formed to illuminate simultaneously both parts of each character with each character being so arranged as to obscure from one viewpoint those portions of the luminous means not required to display the respective character from that viewpoint. The device is so arranged that the characters actually will only be visible from opposed view-points, but for all practical purposes, and in accordance with continuity of vision, the sign will appear to be displayed so as to be visible simultaneously and continuously from all points of the horizon.

In Fig. 1 a portion of the sign is illustrated using one character for the purpose of description. In this connection the device for displaying characters in opposite directions comprises the single character "M" which is in two parts 10 and 11 respectively, each part secured on opposite sides of the rotatable shaft 12 and arranged to represent the character from two op-

posing view-points. In this instance, each part of the character is formed of an open faced channel structure having vertically extending portions 13 and 14 and diagonally extending parts 15 and 16. In this instance the luminous means comprises a gaseous discharge tube 20 which is secured at one end 21 by a gas tight joint to the terminal member 22. The tube extends into the lower portion 23 of one leg of the letter "M," continues upwardly through the part 14, downwardly through the part 16, upwardly through the angularly extending part 15 and downwardly through the other vertical leg 13. The tube then extends out of the bottom 24 of the leg 13 and winds around the shaft 12 as at 25 and then enters the bottom 26 of leg 27 extending upwardly through that leg downwardly through the diagonal section 19 and then again upwardly through the section 18 and downwardly through the leg 17 of the second letter "M." The tube then leaves the bottom 28 of the leg 17 and the angularly extending portion 28 is sealed into the terminal member 30.

Instead of using a luminous tube it is equally feasible to use a plurality of individual lamps connected to provide the necessary illumination for the sign. It is also within the contemplation of this invention that where a multiplicity of characters are used that the continuous tube may extend from the single set of terminals throughout the entire sign as shown in Fig. 8. If desirable or necessary, the sign can be composed of a plurality of individual characters which can be assembled on a shaft to make a composite sign. In such a case, a plurality of slip rings may be necessary to supply the current to the luminous devices.

The parts of the character are arranged to blank out those portions of the luminous means which are not needed for representing the character from one view-point. The portions 21, 25 and 29 of the continuous tubing will also be coated with black paint or obscured from view.

The entire structure as heretofore described is supported on the shaft 12 with the terminal members 22 and 30 being carried by the disc member 31. The terminals, disc, and shaft are provided with the necessary insulation to keep the electrical circuit separate and distinct.

Where a single character is being used in the sign, shaft 12 may be directly driven and rotated by a low-speed motor 32 by having the shaft 33 of the latter and the shaft 12 secured in a coupling member 34 by the set screws 35 and 36. Where the sign is especially large or heavy a more

powerful motor may be used and a gear train connected between the motor and the shaft 12, schematically illustrated in Fig. 8, by the bevel gears 38 and 39, which provide the mechanical connection between the motor 32 and the shaft 12.

For the purpose of supplying the electrical energy to the luminous means, which as heretofore mentioned represents a continuous gaseous discharge tube or a series of electric lamps, the terminals 22 and 30 are connected to an appropriate electrical collector. In this instance, the collector is formed by two concentric rings 40 and 41 which are rigidly mounted on the shaft 12 and insulated from each other by means of the insulating bushing 42, the latter being substantially L shaped in cross section.

Terminal 30 is connected to the upper surface 43 of the ring 41 by means of the electrical connection 44. The terminal 22 is connected by a similar electrical connection comprising lead 45 which is secured to the upper surface 46 of the ring 40. A source of power 47, is connected to the primary 48 of a transformer 49, the secondary 50 of which is connected by leads 51 and 52 to the brushes 53 and 54. The respective brush holders 55 and 56 are insulated from the rough or other structure 57 by means of the insulating box 58 and 59. In this manner, the power from the secondary 50 of the transformer is carried by the conductors and thence to the terminals of the luminous tube thereby providing the necessary illumination.

In Fig. 8 the luminous device is schematically illustrated as being composed of the letters A to G inclusive with a tube extending from the terminal 22' to the terminal 30' and passing through all of the letters. The interconnecting parts of the tubing which are obscured from both viewpoints such as at the points 21, 25, and 28 in Fig. 1 are indicated in this figure at the points 60, 61 and 62.

It will be readily understood that a sign of considerable merit has been described which is relatively simple to fabricate and which will be highly efficient in use.

Variations within the true spirit and scope of this invention are to be determined by the hereto appended claims.

What I claim is:

1. A sign comprising a rotatable shaft, means for rotating said shaft, a pair of oppositely facing characters, means engaging said shaft and said characters fixedly securing said characters on said shaft in substantially parallel relation with one character extending in a direction opposite from the other character, a plate fixed to said shaft, terminal members carried by said plate, illuminating means connected to said terminal members and extending across a face of each character, a pair of collector rings carried by said shaft, means connecting a ring to a terminal member, a wiper engaging each ring, and means connecting said wipers to a source of electric current supply. 5 10 15

2. A sign comprising a rotatable shaft, means for rotating said shaft, a pair of oppositely facing flanged characters, means engaging said shaft and said characters fixedly securing said characters on said shaft in substantially parallel relation with one character extending in a direction opposite from the other character, a plate fixed to said shaft, terminal members carried by said plate, illuminating means connected to said terminal members and disposed between the flanges of said characters, a pair of collector rings carried by said shaft, means connecting a ring to a terminal member, a wiper engaging each ring, and means connecting said wipers to a source of electric current supply. 20 25 30

3. A sign comprising a rotatable shaft, means for rotating said shaft, a pair of oppositely facing flanged characters, means engaging said shaft and said characters fixedly securing said characters on said shaft in substantially parallel relation with one character extending in a direction opposite from the other character, a plate fixed to said shaft, terminal members carried by said plate, gaseous illuminating means connected to said terminal members and disposed between the flanges of said characters, a pair of collector rings carried by said shaft, means connecting a ring to a terminal member, a wiper engaging each ring, and means connecting said wipers to a source of electric current supply. 35 40 45
